CLAIM

The ornamental design for a bucket liner for earth moving vehicles, as shown and described.

DESCRIPTION

FIG. 1 is a perspective view of a first embodiment of a bucket liner for earth moving vehicles;

FIG. 2 is a side elevational view of the first embodiment of a bucket liner for earth moving vehicles;

FIG. 3 is a front elevational view of the first embodiment of a bucket liner for earth moving vehicles, the back being the same in appearance;

FIG. 4 is an opposite side elevational view of the first embodiment of a bucket liner for earth moving vehicles;

FIG. 5 is a top plan view of the first embodiment of a bucket liner for earth moving vehicles;

FIG. 6 is a bottom plan view of the first embodiment of a bucket liner for earth moving vehicles;

FIG. 7 is a perspective view of a second embodiment of a bucket liner for earth moving vehicles;

FIG. 8 is a side elevational view of the second embodiment of a bucket liner for earth moving vehicles;

FIG. 9 is a front elevational view of the second embodiment of a bucket liner for earth moving vehicles, the back being the same in appearance;

FIG. 10 is an opposite side elevational view of the second embodiment of a bucket liner for earth moving vehicles;

FIG. 11 is a top plan view of the second embodiment of a bucket liner for earth moving vehicles;

FIG. 12 is a bottom plan view of the second embodiment of a bucket liner for earth moving vehicles;

FIG. 13 is a perspective view of a third embodiment of a bucket liner for earth moving vehicles;

FIG. 14 is a side elevational view of the third embodiment of a bucket liner for earth moving vehicles;

FIG. 15 is a front elevational view of the third embodiment of a bucket liner for earth moving vehicles, the back being the same in appearance;

FIG. 16 is an opposite side elevational view of the third embodiment of a bucket liner for earth moving vehicles;

FIG. 17 is a top plan view of the third embodiment of a bucket liner for earth moving vehicles; and,

FIG. 18 is a bottom plan view of the third embodiment of a bucket liner for earth moving vehicles.
